ABSTRACT OF THE DISCLOSURE

A device for teaching the effectiveness of the passive tank stabilizer. A small, lightweight article having two oppositely positioned rocker members is partially filled with a stabilizing mass. When placed on one of said rocker members, the device rocks to and fro for a relatively long period of time. When, however, the article is placed on its other rocker member, it rocks for only a brief period of time, thus demonstrating the effectiveness of the passive tank stabilizer.

BACKGROUND OF THE INVENTION

The passive tank stabilizer is well known; many years ago its basic principle was established. However, it was not until recently that this basic principle could be put to a practical use. Today, there are numerous ocean going vessels equipped with passive stabilization systems.

Presently, when it is the desire to demonstrate the effectiveness of a passive tank stabilization system, it is necessary to do so by means of a full-scale vessel appropriately equipped with stabilizing tanks. It is therefore evident that demonstrations cannot presently be made in an economical and readily available manner. Furthermore, in actual on-board demonstrations, it is difficult to demonstrate the difference between stabilized and non-stabilized modes of operation. It is toward the goal of providing an economical and readily available means for demonstrating the effectiveness of the passive tank stabilization system which the present invention is directed.

SUMMARY OF THE INVENTION

The present invention relates to a device for visually displaying the operation of a passive tank stabilizer. It is small and lightweight and can therefore readily be carried by hand. In one mode of its operation, demonstrative of the unstabilized state, it oscillates for long periods of time until frictional forces overcome the oscillatory forces and cause the oscillations to cease. When, however, the device is in its second mode of operation, demonstrative of the stabilized state, oscillatory motion imparted to the device by external forces is readily quenched. Thus, the difference between the stabilized and the unstabilized modes of operation is readily displayed, and, consequently, the effectiveness of the passive tank stabilization system is dramatically demonstrated.

Accordingly, it is one object of the invention to provide a device which readily illustrates the operation of a passive tank stabilization system.

It is another object of the invention to provide a device for readily, economically, and in a compact form, illustrating the differences in operation between a stabilized and an unstabilized system.

In view of its small size, and in view of the low manufacturing costs associated therewith, the device of the present invention can readily be distributed by manufacturers of stabilization systems for purposes of advertising. Accordingly, it is another object of the inven-

2

tion to provide a small and inexpensive device for advertising and, at the same time, displaying a passive tank stabilization system.

In view of its small size, its low cost of manufacture and the surprising results its portrays, the present invention makes for an economical, effective and conversational paper-weight. Accordingly, it is another object of the invention to provide a paper-weight in combination with an amusement device. For purposes of providing a toy or amusement device, the device should be made of a non-transparent material. Thus, the difference between the first and second modes of operation is mystically portrayed.

Since the device of the present invention is inexpensive to manufacture and is small and lightweight, it can be quite effective in the stabilization of toy boats. Therefore, it is still a further object of the invention to provide a system for stabilizing toy boats.

The present invention depends, for its operation, upon the basic principle of operation of the passive tank stabilizer. This principle is that if a mass moves 180° out of phase with a parent device, the parent device can be made to rock for long periods of time. When, however, the mass is made to move 90° out of phase with the movement of the parent device, the mass serves to stabilize the parent device and therefore to quickly damp any rocking movement therein.

While in a preferred embodiment, the invention is shown as relying upon the operation of a liquid, it should be noted that any flowing stabilizing mass could be used. For instance, in one mode of operation, a ball could be fixed in position, thus demonstrating the unstabilized mode; in the second mode of operation, the ball could move 90° out of phase with the device, thus demonstrating the stabilized mode.

Also, while the device is shown as comprising a central body region with a pair of appended rocker members, it should be noted that the device may be manufactured with a unitary body forming a pair of rocker surfaces.

Other objects of the invention, as well as many of the attendant advantages thereof, will become more readily apparent when reference is made to the following description taken in conjunction with the accompanying drawings.

BRIEF DESCRIPTION OF THE DRAWINGS

FIG. 1 is a front view of the apparatus of the present invention:

FIG. 2 is a side view of the invention shown in FIG. 1;

FIG. 3 is a front view of the invention with its front plate removed and in its stabilized mode of operation;

FIG. 4 is a front view of the invention with its front plate removed and in its unstabilized mode of operation;

FIG. 5 is a cross-sectional view through line 5—5 of FIG. 3.

FIG. 6 is a cross-sectional view through line 6—6 of FIG. 3;

FIG. 7 is a cross-sectional view through line 7—7 of FIG. 4; and

FIG. 8 is a cross-sectional view through line 8—8 of FIG. 4.

DETAILED DESCRIPTION OF THE INVENTION

With reference first to FIGS. 1 and 2, the device of the present invention is shown generally at 10. The display device 10 comprises a first rocker member 12 and a second rocker member 14, each being of an arcuate shape. Intermediate the rocker members 12 and 14 is a central body region 16 which, as is seen best in FIG. 2, houses

a stabilizing mass in the form of a body of liquid 18. The central body region 16 is in the form of a chamber which is defined by a pair of side walls 38, a pair of end walls 40, a first floor member 42 which is associated with the unstabilized mode of operation and a second floor member 44 which is associated with the stabilized mode of operation. Attached to one of the side walls 38 is a plate 20 which conveniently serves as a means for displaying any name, trademark, decoration, or advertisement.

With reference now to FIGS. 3, 5, and 6, depicting the apparatus of the present invention when in its stabilized mode of operation, the device is shown resting on its rocker member 12. In this position, the liquid 18 housed within the chamber 16 can be viewed as occupying three separate volumes. These separate volumes are defined by a central chamber 22 and a pair of end chambers 24. Serving to define the three individual chambers is a transparent block 26 and a pair of transparent strips 28. The block 26 and strips 28 are shown to extend from the wall 44 of the central chamber 16 nearest the rocker member 12 to the wall 42 of the central chamber 16 nearest the rocker member 14. However, the block 26 and the strips 28 may be constructed to extend toward the wall 42 only an amount necessary to ensure that the liquid 16 never passes thereabove when the device 12 rests on the rocker member 12.

It will be noted that when the article is resting on its rocker member 12, the liquid 18 is housed in what may be termed a C-tank. This can best be seen in FIG. 5. It should also be noted that when the liquid 18 is passing from one end chamber 24 to the other, it passes through a pair of nozzles 30, each nozzle being formed by a portion of the block 26 and a respective strip 28. For best results, the liquid level in the tank should be slightly higher than that necessary for resonance between the liquid oscillations and the natural frequency of the device.

Reference is now directed to FIG. 4 and its associated sectional views, FIGS. 7 and 8, each showing the article of the present invention in its non-stabilized position of operation. When the article 10 rests on its rocker member 14, the liquid 18 housed within the central chamber 16 can be said to occupy a plurality of volumes. These volumes are defined by chambers 32 which are formed by a plurality of parallel and spaced elements 34 extending from the wall 42 of the chamber 16 upwardly and toward the wall 44 an extent sufficient to ensure that the liquid 18 does not pass thereover. While the elements 34 serve to define the chambers 32, it should be noted that the elements do not entirely isolate one chamber from its neighbors. This is best seen in FIG. 8. More particularly, each element 34 abuts the wall 42 over a substantial portion of said wall. However, the extreme ends of each element 34 is bevelled in such a manner as to provide passages 36 for the flow of liquid from one chamber 32 to its neighbor chambers. In this way, a constant list is avoided.

The operation of the device 10 forming the present invention is first described with reference to the unstabilized condition shown in FIG. 4, there then following a description of the invention with reference to the stabilized condition shown in FIG. 3.

With reference again to FIG. 4, the device 10 is shown resting on its rocker member 14. By an external force, the device is rolled along the rocker until it experiences a substantial list relative to its steady state position shown in this figure. When released, the device 10 rocks to and fro on the rocker member 14, and only after the frictional forces associated with such rocking overcome the motion, does the device stabilize. This stabilization occurs after approximately twenty-five oscillations.

When, however, the device 10 is in the position indicated in FIG. 3, stabilization occurs rapidly. To demonstrate the rapid stabilization brought about by passive tank stabilization systems, the device 10 is rolled along its rocker member 12 until it experiences a substantial list. The device is then released. Due to the effect of the liquid

in the chamber 16, and more particularly in the C-tank effective in this mode of operation, the device rocks along its rocker member 12 for only a short period of time. The rocking is quieted by an action similar to that present in a ship equipped with a passive tank stabilization system and is quieted after approximately two oscillations.

Thus, when comparing the operation in its unstabilized and stabilized modes of operation, the device 10 rocks more than ten times as long in its unstabilized state as it does in its stabilized state. It is therefore readily apparent that the device of the present invention is quite dramatic in illustrating the effectiveness of a passive stabilization system.

It should be noted that the device of the present invention is intended merely to illustrate the effectiveness of a stabilization system. Therefore, it is to be understood that the mode of operation termed the unstabilized mode is not necessarily representative of an unstabilized vessel, for instance. Rather, the elements 34 are inserted in the device 10 only to cause the device to uncontrollably rock in its unstabilized mode. On the other hand, the configuration of the C-tank effective in the stabilized mode of operation is, in fact, a tank that can be incorporated in an ocean going vessel. In view of the above, it should be noted that the unstabilized mode of operation may be perfected by means other than the elements 34; likewise, the stabilized mode may be perfected by means other than the C-tank shown and described.

As noted above, the device of the present invention has been described with reference to a preferred embodiment. It is the intent, however, that the invention not be limited thereto, since many substitutions and modifications will become apparent to those skilled in the art, but be limited only as defined in the appended claims.

35 What is claimed is:

1. A device, having two modes of operation, for demonstrating the operation of a passive tank stabilization system, and comprising: a closed chamber; a stabilizing mass partially filling said closed chamber for stabilizing 40 said device when in its first mode of operation; and means for preventing said stabilizing mass from stabilizing said device when in its second mode of operation.

2. The invention as recited in claim 1, wherein said chamber includes first phase means associated with said 45 first mode of operation for maintaining the phase between the position of the device and the position of the stabilizing mass near 90°; and second phase means associated with said second mode of operation for maintaining the phase between the position of the device and the position of the stabilizing mass near 180°.

3. The device of claim 1 wherein said stabilizing mass is a liquid and wherein said first and second phase means comprise first and second tanks for housing said liquid when said device is in its first and second mode of operation, respectively.

4. The invention as recited in claim 3 wherein said second phase means serves to substantially eliminate the flow of liquid from one end to the other of said second tank.

60 5. The invention of claim 3 wherein said second phase means is formed by a plurality of elements parallel to and spaced from one another, said elements being fixedly secured to one wall of said closed chamber, said one wall serving as the bottom of said second tank when the device is in its second mode of operation.

6. The invention as set forth in claim 5 wherein said elements extend from said one wall of said chamber an amount sufficient to ensure that the liquid housed in said chamber does not pass over said elements when said demonstration device is in its second mode of operation.

7. The invention as recited in claim 5, wherein said elements have a maximum width corresponding to the internal width of said chamber and wherein said elements are fixedly secured to said one wall of said chamber

for only a portion of their width to allow for slight communication past each element.

8. The invention as recited in claim 7 wherein said elements are secured to said one wall in such a manner that small passages are formed between said one wall and each of said elements at the extremities of each of said elements.

9. The invention as recited in claim 3 wherein said first phase means is defined by a block of material secured to a side wall of said chamber, wherein said block is positioned centrally with respect to the length of said chamber.

10. The invention as set forth in claim 9, and further comprising: first and second strips of material fixedly attached to a second side wall of said chamber opposite the wall serving to support said block of material, said first and second strips being positioned, respectively, adjacent the extremities of said block and each forming a nozzle with the respective extremity of said block.

11. The invention as recited in claim 10 wherein said block and said first and second strips extend from the wall of said chamber serving as the bottom of said first tank when the device is in its first mode of operation, an amount sufficient to ensure that the liquid housed in said chamber cannot pass over said block and strips when said demonstration device is in its first mode of operation.

12. The invention as defined in claim 1 wherein said device is of a transparent material.

13. The invention as defined in claim 1 wherein said device is of a non-transparent material.

14. The invention as defined in claim 5 wherein said first phase means is defined by a block of material secured to a side wall of said chamber, wherein said block is positioned centrally with respect to the length of said chamber.

15. The invention as described in claim 14, and further comprising first and second strips of material fixedly attached to the side wall of said chamber opposite the side wall serving to support said block of material, said first and second strips being positioned, respectively, adjacent the extremities of said block and each forming a nozzle with the respective extremity of the said block.

16. The device of claim 1, wherein said device is of unitary construction.

17. The invention as recited in claim 1, and further comprising first means for rocking said device when in its first mode of operation and second means for rocking said device when in its second mode of operation.

18. A device for demonstrating the operation of a passive tank stabilization system, and comprising: a main body portion forming a closed chamber partially filled with a stabilizing mass; first means positioned adjacent one wall of said main body portion for rocking said demonstration device; second means adjacent an opposite wall of said main body portion for rocking said demonstration device; first tank means within said main body portion operative only when the device is positioned on said first rocker means, said first tank means serving, when operative, to control the flow of said stabilizing mass in said main body portion in such a manner that an initial oscillation imparted to the demonstration de-

vice is sustained for a long period of time; and second tank means within said main body portion operative only when the device is positioned on said second rocker means, said second tank means serving, when operative, to control the flow of said stabilizing mass in said main body portion in such a manner that an initial oscillation imparted to the demonstration device is rapidly quieted.

19. The device as described in claim 18, wherein said first tank means comprises a plurality of chambers operative when said device is positioned on said first rocker means and wherein said chambers are formed on the wall of said main body portion adjacent said first rocker means.

20. The invention of claim 19, wherein said chambers of said first tank means are formed by means of a plurality of elements parallel to and spaced from one another, said elements being fixedly secured to the wall of said main body portion adjacent said first rocker means.

21. The invention as recited in claim 18, wherein said second tank means comprise a plurality of chambers adjacent said second rocker means.

22. The invention as recited in claim 21, wherein said chambers of said second tank means are defined by means of a block of material secured to one wall of said main body portion, wherein said block extends between said first and said second rocker means, and wherein said block is positioned centrally with respect to the length of said main body portion.

23. The invention as set forth in claim 22, and further comprising: first and second strips of material fixedly attached to the wall of said main body portion opposite the wall serving to support said block means, said first and second strips being positioned, respectively, adjacent the extremities of said block means and each forming a nozzle with the respective extremity of said block means.

24. The invention as defined in claim 20, wherein said second tank means comprises a plurality of chambers adjacent said second rocker means, wherein said chambers of said second tank means are defined by means of a block of material secured to one wall of said main body portion, wherein said block extends between said first and said second rocker means, and wherein said block is positioned centrally with respect to the length of said main body portion.

25. The invention as described in claim 24, and further comprising first and second strips of material fixedly attached to the wall of said main body portion opposite the wall serving to support said block means, said first and second strips being positioned, respectively, adjacent the extremities of said block means and each forming a nozzle with the respective extremity of said block means.
